HENRY E. BORGER AND JULIUS H. RICHARDS, OF NEWARK, NEW JERSEY, ASSIGNEES
TO SPLITDORF ELECTRICAL COMPANY, OF NEWARK, NEW JERSEY.

MOUNTING-PLATE.

1,249,308.

Specification of Letters Patent. Patented Dec. 11, 1917.

Application filed June 30, 1915. Serial No. 37,224.

To all whom it may concern:

Be it known that we, HENRY E. BORGER and JULIUS H. RICHARDS, citizens of the United States, residing at Newark, in the 5 county of Essex and State of New Jersey, have invented new and useful Improvements in Mounting-Plates, of which the following is a specification.

This invention relates to mounting plates 10 adapted for installing motors, dynamos, magnetos and the like on any prime mover, such as an internal combustion engine, although the application is not limited to any particular kind of prime mover.

In making installations on internal combustion engines as installed in moving vehicles, such as automobiles, particularly those not originally equipped with starters or lighting generators, it is found difficult to 15 install an ordinary type of plate or bracket on such engines and get proper alinement of the driving elements, and much time is lost in fitting the bracket or mounting plate.

In order to make installations of this character, it has become common practice to use 20 noiseless chains for the driving medium between a sprocket, mounted on the driving shaft, such as the crank shaft of the engine and a sprocket mounted on the dynamo, motor, magneto or whatever device is 25 required to be driven.

Our invention relates to means for overcoming the difficulties encountered by such installation by providing a mounting plate 30 or bracket support that is readily adjustable in two directions. That is, one adjustment for the purpose of bringing the driving centers in the same plane and another adjustment for giving the proper tension on the 35 chain or belt, whichever is used.

Another object of our invention is to provide a mounting plate through whose instrumentalities the dynamo, magneto, motor, etc., which is carried on the plate, can be 40 turned back away from the engine in case any work is required to be done on the engine without dismounting the dynamo, motor, magneto or the like from that portion of the plate to which it is attached.

50 Other and further objects of our invention will be apparent after an inspection of

the drawings, which form a part of the specification.

Figure 1 shows an end view of an engine of a well known type with a portion of the 55 frame, which supports the engine and having the mounting plate attached thereto and the plate carrying a motor-dynamo.

Fig. 2 is a top plan view of the mounting plate with the motor-dynamo removed. 60

Fig. 3 is an end elevation of Fig. 2.

Referring now particularly to the drawings in which like numerals refer to corresponding parts in the various figures, 1 represents the front cylinder of a well known 65 type of multi-cylinder engine, 2 is the crank shaft of the engine on which is mounted a sprocket wheel 3. 4 is the front cross member of the chassis to which is attached the usual fender 5. 6 is a sub-structure or base 70 of the mounting plate having legs 7 and 8 which are fastened to the edge of the crank case by the bolts 9, passing through holes 10 and 11 in the legs 7 and 8, and through the corresponding holes which have already 75 been provided in the flange of the crank case to accommodate the fastening bolts previously used to secure the two portions of said crank case together. The upper part of the mounting plate 6 has a projection 12 with 80 a hole 13 therein. A bolt 14 passes through the hole 13 and fastens the projection 12 to a lug cast on the wall of the engine. Said lug, as is well known, is usually provided on the frame of engines of this type, and serves 85 as a seat for a bolt used to fasten the crank shaft bearing cap in position. The legs 7 and 8 are properly ribbed in order to give strength thereto. The upper rear portion of the part 6 carries two lugs 15 and 16, through 90 which passes a rod 17 that is held in a stationary position in lugs by means of pins 18 and 19. The rod 17 projects beyond the lugs 15 and 16 and on these projections is slidably carried a super-structure or plate 95 20 by means of two projecting lugs, 21 and 22. Between the lug 21 and lug 15 there is a clearance space 23 and between the lugs 16 and 22 a clearance space 24. On one projecting end of rod 17 is a lock washer 25 and a nut 26, while on the other end of the 100 rod 17 is a lock washer 27 and nut 28, the

purpose of which will be explained later. The plate 20, as illustrated, contains three holes 29 through which bolts 30 pass into the base of the motor-dynamo 31, which carries a 5 sprocket 32, properly keyed or fastened to the armature shaft. In the forward end of the plate 20 there are two set screws 33 and 34 for the purpose of adjusting the plate 20 up and down. After the entire mounting 10 plate has been installed on the engine and the motor-dynamo 31 or any other device required to be driven, is fastened to the plate 20, the driving chain which has been previously made of a length practically correct, 15 is put in place and set screw 34 turned down until the proper tension of the chain or belt is obtained. The lock nut 35 is then set up and as an additional precaution, the additional set screw 33, which carries the collar 20 36 fastened in position thereon by the pin 37 and which engages threads in the bottom part of the mounting plate 6 is turned downward until the collar 36 pinches against the plate 20. It will be readily seen that by 25 manipulating the set screws 33 and 34, an adjustment of the chain or belt is quickly obtained. Any other suitable means of locking the two portions of the mounting plate together may be used as we do not wish to 30 be limited to any particular method of doing this.

Should it be found that sprockets 3 and 32 be not in proper alignment, then the 35 plate 20, upon which the motor-dynamo 31 is carried can be moved forward or back by manipulating nuts 26 and 28, by loosening one and tightening the other in accordance with the direction required, the spaces 23 and 24 being provided to allow for this 40 adjustment. It will be seen that an important feature of our invention is that these adjustments may be made while the machine is in operation.

Should it be found necessary to do any 45 work on the engine, and the motor dynamo 31 is at all in the way, the driving chain or belt can be loosened by means of the set screws 33 and 34 or their equivalent, the chain removed from the sprocket 32 and the 50 entire plate 20 with the motor-dynamo can be turned back as shown in the dotted position of Fig. 1.

In the particular plate, as illustrated in Fig. 2, only three bolt holes 29 are shown 55 for fastening the motor-dynamo 31 to the plate 20, which is shown cut off on one side at an angle. The object of this is to clear a certain pipe on the particular engine to which this plate is applicable.

60 It will thus be apparent to anyone skilled in the art that numerous changes and alterations may be made in the details of our mounting plate but these alterations and changes are believed to come within the 65 scope of the appended claims.

Having thus described our invention, what we claim is:—

1. In a mounting plate for dynamo electric machines, the combination of a sub-structure, a super-structure attached to said 70 sub-structure, supporting means for said sub-structure and adjusting means for adjusting the super-structure in two directions with reference to said sub-structure.

2. In a mounting plate, the combination 75 of a sub-structure having lugs thereon and a support therefor, a rod carried by said lugs, a super-structure having lugs adapted to receive said rod, means on said rod for adjusting said super-structure in a horizontal 80 direction, and means coöperating between the super and sub-structures for adjusting the super-structure in a vertical direction.

3. In a mounting plate, the combination 85 of a base having lugs thereon and means for supporting said base, a rod supported in a fixed position on said lugs, a plate pivotally mounted on said rod, means for adjusting said plate on said rod, in a horizontal direction, and means coöperating between the 90 base and plate for adjusting the plate in a vertical direction.

4. In combination, a prime mover, a mounting plate attached thereto, said mounting plate having a sub-structure and a super-structure, said super-structure being pivotally mounted on said sub-structure, a mechanism to be driven and means for attaching the same to said super-structure, means for 100 driving said mechanism on said super-structure from said prime mover and means for adjusting said driving means in two directions.

5. In combination, an internal combustion 105 engine having a driving shaft, and a driving member thereon, a mounting plate having a sub-structure and a super-structure and means for attaching said sub-structure to said engine, said super-structure being rotatably mounted on said sub-structure, an 110 electric generator mounted on said super-structure, means for driving said electric generator from the driving member on said engine, and means on said mounting plate 115 for adjusting said driving means in both a horizontal and vertical direction.

6. In combination, an internal combustion engine, an electric generator, a mounting plate adapted to carry said generator and 120 means for fastening said plate to said engine, a driving member on said engine, a driven member on said electric generator, driving means between said driving and driven members, and means on said mounting plate 125 for adjusting the driving centers of the driving and driven members in two directions.

7. In a system of the character described, the combination, with an automobile engine and its crank shaft, of a main non-adjust- 130

able supporting plate provided with points of attachment corresponding to established points of attachment in relation to said engine and its crank shaft, an auxiliary plate supported entirely by said main plate and adjustably connected therewith, starting devices located on said auxiliary plate,

and a driving connection including a chain from said starting devices to said crank shaft.

10

In witness whereof we affix our signatures.

HENRY E. BORGER.
JULIUS H. RICHARDS.
